US00D911825S

(12) **United States Design Patent** (10) **Patent No.:** **US D911,825 S**
(45) **Date of Patent:** **** Mar. 2, 2021**

(54) **LOCKING CABLE ROTATION TOOL**

(71) Applicant: **Innovatech, LLC**, Chicago, IL (US)

(72) Inventor: **Bruce Nesbitt**, Chicago, IL (US)

(73) Assignee: **Innovatech, LLC**, Chicago, IL (US)

(**) Term: **15 Years**

(21) Appl. No.: **29/679,256**

(22) Filed: **Feb. 4, 2019**

(51) **LOC (13) Cl.** **08-08**

(52) **U.S. Cl.**

USPC **D8/359**; D8/330; D8/323

CLAIM

The ornamental design for a locking cable rotation tool, as shown and described.

DESCRIPTION

FIG. 1 is a top front perspective view of a locking cable rotation tool of my new design.

FIG. 2 is a left side view of the locking cable rotation tool of FIG. 1.

FIG. 3 is a right side view of the locking cable rotation tool of FIG. 1.

FIG. 4 is a front view of the locking cable rotation tool of FIG. 1.

FIG. 5 is a rear view of the locking cable rotation tool of FIG. 1.

FIG. 6 is a top view of the locking cable rotation tool of FIG. 1; and,

FIG. 7 is a bottom view of the locking cable rotation tool of FIG. 1.

The broken lines shown represent unclaimed subject matter and form no part of the claimed design.

1 Claim, 7 Drawing Sheets
